J. GREGG.
WATER COCK.

No. 89,143.

Patented Apr. 20, 1869.

INVENTOR:

Joseph Gregg

JOSEPH GREGG, OF MANCHESTER, NEW HAMPSHIRE.

Letters Patent No. 89,143, dated April 20, 1869.

IMPROVEMENT IN WATER-COCKS.

The Schedule referred to in these Letters Patent and making part of the same.

To all whom it may concern:

Be it known that I, JOSEPH GREGG, of Manchester, in the county of Hillsborough, and State of New Hampshire, have invented a new and improved Water-Cock; and I do hereby declare that the following is a full, clear, and exact description thereof, which will enable others skilled in the art to make and use the same, reference being had to the accompanying drawings, forming part of this specification, in which—

Figure 1 represents a part sectional view of the invention

Figure 2 represents a sectional and inside view of the tube.

Figure 3 is a plan of the elastic diaphragm.

Similar letters of reference indicate like parts.

This invention relates to a water-cock, constructed air-tight, with a view to prevent all leakage and waste, and which shall be self-closing.

The invention consists—

First, in a tubular valve-stem, with suitable guides, and spiral spring.

Second, in the adjustment of an elastic diaphragm of rubber, through the centre of which the discharge-tube is passed, and held in position by a flange inside the chamber, upon its upper surface, and by a screw-cap on its lower surface.

Third, in the use of a flanged guide-tube, into the lower part of the interior of which the discharge-tube is screwed, and which serves, when pressure upward is applied to its flange, to raise the valve from its seat, and permit the exit of the water through the perforations of the discharge-tube.

A represents the discharge-chamber of the cock, divided into two compartments by the partition which forms the valve-seat B.

B represents the partition, forming the valve-seat.

C is the valve.

D is the screw-cap, covering the upper part of the discharge-chamber, and hollowed to receive and serve as a guide for the valve-stem E, as it is raised or depressed, and also to confine the spiral spring F, which encircles the valve-stem.

E is the valve-stem.

F, the spiral spring, which serves, in combination

with the elastic diaphragm, to keep the valve in its proper place when not in use.

G is the discharge-tube, through the perforations of which, H H, the water is permitted to flow, whenever upward pressure is applied to the flanged guide-tube I.

I is the flanged guide-tube.

J represents the screw-cap, applied to the bottom of the cock-chamber, and which serves, in combination with the flange of the lower chamber, to confine in place the elastic diaphragm.

K is the elastic diaphragm, of rubber, or its equivalent, through the centre of which the discharge-tube passes, serving thereby to close all connection between the lower chamber and space through which the guide-tube passes, thereby preventing leakage, and also serving, by its elasticity, to draw down the discharge-tube, and closing the valve C.

L L are two metallic washers, applied respectively to the upper and under surface of the diaphragm K, and encircling the discharge-tube G, and giving firmness to the movements of the elastic diaphragm K.

The prime object of this invention is to supply to manufactories, tenement-houses, and other localities where aqueduct-water is in use, a faucet, which shall be self-closing, free from leakage, not liable to get easily out of repair, and which is capable of preventing the undue waste of water and damage frequently arising where water-cocks have been left open by carelessness, or with the intention of preventing freezing during the night-time.

Having thus described my invention,

I claim as new, and desire to secure by Letters Patent—

A water-cock, operated by means of the concentric tubes I and G, and the diaphragm K, as and for the purposes specified.

The above specification of my invention, signed by me, this 13th day of August, 1868.

JOSEPH GREGG.
